DESIGN FOR A PIN

Irving Apisdorf, New York, N. Y.

Application July 15, 1941, Serial No. 102,153

Term of patent 3½ years

To all whom it may concern:

Be it known that I, Irving Apisdorf, a citizen of the United States, residing in New York city, in the county of New York and State of New York, have invented a new, ornamental, and original Design for a Pin, of which the following is a specification, reference being had to the accompanying drawing, forming part thereof.

I claim:

The ornamental design for a pin, substantially as shown.

IRVING APISDORF.
